UNITED STATES PATENT OFFICE.

HENRY K. CHRIST, OF MAHANOY CITY, PENNSYLVANIA.

GAME APPARATUS.

No. 836,632.

Specification of Letters Patent.

Patented Nov. 20, 1906.

Application filed January 29, 1906. Serial No. 298,494.

To all whom it may concern:

Be it known that I, HENRY K. CHRIST, a citizen of the United States, residing at Mahanoy City, in the county of Schuylkill and State of Pennsylvania, have invented new and useful Improvements in Game Apparatus, of which the following is a specification.

My invention relates to improvements in game apparatus, and has particular relation to apparatus of this character in which a projectile is driven over the face of the base-board, its final position upon cessation of its movement determining the result of the particular "shot."

The object of my invention is to provide an apparatus especially applicable to the playing of the game of "indoor base-ball," in which the face of the board forming the base is marked into divisions each of which designates some well-known term in the game of base-ball and which during the course of the game have an effect on the result of the game and in connection with such marked face to provide a runway for the projectile leading to the face in a direction toward the center of the board, together with the provision of suitable projectile-deflectors positioned on the face of the base-board in such manner as to render the "placing" of the projectile on any particular division somewhat difficult.

A further object is the provision of suitable counting or tallying means for scoring during the progress of the game.

To these and other ends, the nature of which will be readily understood as the invention is hereinafter fully described, illustrated in the accompanying drawings, and particularly pointed out in the appended claims, said invention consists in the game apparatus hereinafter described and claimed.

In the accompanying drawings, Figure 1 is a plan or face view of the board. Fig. 2 is a sectional view taken on line 2 2 of Fig. 1.

Similar reference characters represent similar parts in both of the figures.

The game-board which comprises substantially the complete apparatus, the projectile being of any suitable character, such as a rubber ball, (not shown,) consists of a base-board 5, which may be square or rectangular in form, as desired, having at one of its sides a projecting portion or lip 6, the lip being preferably arranged at the center of such side. The edges of the board are provided 55 with vertically-extending flanges 7, these

flanges being carried around the sides of the lip 6, thereby forming an inclosed surface on the board with the exception of the end of the lip 6, which is left open. This inclosed surface may be termed the "playing field." 60 If desired, the flanges adjacent to the end of the lip 6 may be cut away, as shown in Fig. 2.

As shown, the sides of the lip 6 are inclined toward each other, with the result that the flanges thereon provide a surface of increased 65 width toward the main portion of the board, which surface forms the runway for the projectile. This runway is continued by the curved edges 8 8 of blocks or raised portions 9 9, located on each side of the lip 6 within 70 the flanges 7 of the lipped side.

The board has its surface marked off into divisions, the principal one of which is in the form of a diamond, representing the base-ball diamond, and at the points thereof are located suitable deflectors 10, consisting of projections covered with rubber or other suitable facing. These deflectors correspond to the several "bases," including the "home" base, and, as shown, the deflectors located 80 at the home base and "second" base are in alinement with the center of the runway, but distant from the exit or throat thereof. The lines of the diamond leading from the home base are carried to the edge of the board and 85 correspond to the "foul-lines" of the game of base-ball. At suitable points on the foul-line are mounted stops 11 11, which extend into foul territory and have the effect of materially stopping the progress of the projectile when brought into contact therewith. 90

Lines 12 are drawn from the foul-line adjacent to the stops 11 to second base, providing a division on the outer side of the diamond, within which are located deflectors 13, 95 corresponding in position to those usually occupied by the second baseman and "short-stop." At a suitable distance from second base a curved line 14 is placed, on which line a number of deflectors 15 (preferably four in 100 number) are located corresponding to the "fielders" of the game. Between the line 14 and the edge of the board a curved line 16 is placed, from the center and ends of which lines 17 are drawn, leading to the several deflectors 15, thereby providing other divisions on the face of the board.

That portion of the face of the board within the foul-lines is divided by lines to form divisions, as shown, while a line connecting 110

"first" and "third" bases divides the diamond. Between the home base and the throat of the runway two deflectors 18 are placed as guards to render more difficult the placing of the ball or projectile.

5 The several divisions formed by the several lines may be colored, if desired, those having the same significance being of the same color, thus aiding in readily determining the result of the shot. As shown, each division is given some distinct name well known in the nomenclature of base-ball, those having the highest value being placed at the points more difficult to reach in the 10 playing of the game. For instance, a "first-base hit" is made if the ball or projectile finally rests in the diamond in the division adjacent to second base. Similar results are obtained when the resting-place of the projectile is on either of the divisions marked 15 "second-base hit," "third-base hit," or "home-run hit." When this occurs, the player moves a counter or checker around the lines of the diamond to the base indicated by the result of the shot. When, however, the projectile comes to rest on the divisions marked "out," "foul," "strike," or 20 "ball," the same effect is produced as occurs in playing the game of base-ball.

25 30 The game may be played by two or more players and is started by one of the players placing the ball or projectile adjacent to the mouth of the runway within the space or field 19. The ball is then struck by the finger or hand of the player, or, if desired, a cue or similar implement may be used, and driven through the runway onto the surface of the board, its course thereover being deflected by the deflectors and stops until it 35 finally comes to rest on one of the divisions on the board. The result of the shot is then tallied, either on the counters, hereinafter described, or by the movement of the checkers 20, as the case may be. This is followed by 40 45 a shot by the next player on the same "side," (or by the same player, if but two players are using the game,) whose score is counted to that of the first player, this being continued until the side is "out," when the opponents 50 take their turn in similar manner, thereby completing an "inning." The side having the most "runs" at the close of the innings wins the game.

The tallying mechanism or counters are 55 located on the blocks 9 and are of any preferred form. Those shown in the drawings comprise a pointer 22, adapted to traverse the circles surrounding them, said circles having numbered divisions, as shown. The 60 pointer is provided with a thumb-piece 23 and is mounted on the block in such manner as to be frictionally held in the position in which it is placed. There are preferably six of these counters, two indicating the number 65 of runs scored by each side and one each for

the strikes, balls, and outs of the side "at bat." The sixth counter records the number of innings played.

It will be readily understood that while the deflectors 18 tend to make difficult the placing of the projectile or ball, yet the presence of the runway of gradually-increasing width toward the playing-surface of the board enables the player to drive his ball in different directions. This coupled with the fact that 75 the ball may be driven with various speeds permits a skilful player to use his judgment in playing the game.

It will be seen that substantially all of the paraphernalia required in the playing of the 80 game is contained on the board and arranged in such manner as to be practically free from injury. The ball or projectile and the checkers being of any preferred character are readily replaced if lost or mislaid.

Having thus described my invention, what I claim as new is—

1. In a game apparatus, a game-board comprising a base-board having an inclosed playing-surface with a divided field including 90 a "diamond," a throat leading onto said surface and opening directly toward one of the points of said "diamond," and deflectors mounted on said board, the number of deflectors including one at each of the points of said 95 "diamond."

2. In a game apparatus, a game-board comprising a base-board having an inclosed playing-surface with a divided field including a "diamond," a throat leading onto said surface and opening directly toward one of the points of said "diamond," and deflectors mounted at predetermined points on said field, the number of deflectors including one at each of the points of said "diamond" and 100 a pair of deflectors located between said throat and the nearest point of the "diamond," said latter deflectors being spaced 105 relatively to each other.

3. In a game apparatus, a game-board 110 comprising a base-board having an inclosed playing-surface with a divided field including a "diamond," a throat leading onto said surface and opening directly toward one of the points of the "diamond," blocks or raised 115 portions located on said surface adjacent to said throat, said blocks having curved edges to form a continuation of the throat, and tallying devices mounted on said blocks.

4. In a game apparatus, a game-board 120 having an inclosed playing-surface provided with an entrance-throat, said board having a divided field, the divisions of said field including a "diamond" opposite said throat, the "diamond" being divided to provide an 125 "out" and a "first-base-hit" space, two curved lines at different distances beyond the "diamond," the field between the "diamond" and the first curved line being divided to form two "out" spaces adjacent to 130

the "diamond" and a "second-base-hit" space, the field between the two curved lines being divided to form "out" and "third-base-hit" spaces, and the field beyond the outer curved line forming a "home-run-hit" space.

5. In a game apparatus, a game-board having an inclosed playing-surface provided with an entrance-throat, said board having a divided field, the divisions of said field including a "diamond" opposite said throat, the "diamond" being divided to provide an "out" and a "first-base-hit" space, two curved lines at different distances beyond the "diamond," the field between the "diamond" and the first curved line being divided to

field between the two curved lines being divided to form "out" and "third-base-hit" spaces, and the field beyond the outer curved line forming a "home-run-hit" space, said board also having deflectors, the number of which include one at each of the points of said "diamond," one in each of the "out" spaces adjacent to the "diamond," and a plurality of deflectors located on the first curved line.

20 In testimony whereof I have affixed my signature in presence of two subscribing witnesses.
